UNITED STATES PATENT OFFICE.

HEINRICH JUCHO, OF DORTMUND, GERMANY.

BUILDING STRUCTURE.

Application filed April 9, 1925, Serial No. 21,903, and in Germany May 3, 1924.

In English specification No. 187,197 a description is given of flat or curved structural partitions, such as walls, frame or lattice-work, roofs and the like, which consists of a 5 number of similar bars or battens crossing each other, which are so arranged that the bars in one direction are secured to each other approximately at the centre of the adjoining 10 continuous bars of the other direction and are in this manner combined to form a network of bars filling a certain space, which network is unyielding to strains in any direction.

In practice these structural partitions, especially for roofs, have hitherto always been constructed of wood, and endeavours have 15 vainly been made to transfer to practical use the iron construction mentioned as possible in the specification, because such construction 20 has been found to be too heavy and too expensive when made of iron.

Now according to the present invention this drawback is mitigated due to the fact 25 that for the bars from which the structural part is composed use is made of iron elements of special shape or formation.

The elements found to be suitable for this purpose comprise expanded truss girders which are so formed that in the centre they 30 are able to withstand considerable strain and that they absorb the transverse forces of stresses in an efficient manner through the binding-pieces or ties.

By the term "expanded truss girders" is 35 meant girders which are formed by slotting the webs of girders and then expanding the girders laterally causing the slotted webs to expand each into a lattice-work of brace-struts.

40 In the accompanying drawings a constructional form of the invention is shown by way of example.

Figure 1 and 2 are elevations of two girders of suitable form.

45 Figures 3 and 4 are sections, on a larger scale, of the assemblage of three girders at a point of abutment, taken along lines A—A of Fig. 4 and B—B of Fig. 3 respectively.

Figure 5 is a perspective view showing 50 part of a curved hall roof.

The expanded truss girder as shown in Figures 1 and 2 is so formed that it is capable of absorbing a great momentum in the centre and the transverse forces or stresses are 55 extensively taken up by the binding pieces or ties. Especially suitable for this purpose

is the form, shown in the drawings, with parabolic binding pieces; furthermore also the form with trapezoidal binding pieces or ties as shown in Figure 2. In order to enable such girders to be combined, in the manner set forth in English specification No. 187,197, so as to form individual units of a skeleton or other structure, they are provided in the centre with plates *b* either riveted or 60 fastened in any other way thereto, which plates carry angle-irons *c* to which the free ends *e*, projecting beyond the ties *d* of the other girders to be connected to the first girders, can be fastened by means of screw bolts, 65 rivets or the like.

In Figures 3 and 4 there is shown upon a larger scale the joint-connection between two girders *a*¹ and *a*² extending in the same direction and a girder *a*³ extending in a transverse 75 direction. The girders *a*¹ and *a*² are secured to about the medial part of the continuous girder *a*³.

The joint-connection between the two girders can, of course, also be effected in any 80 suitable manner.

The roof shown in Fig. 5 comprises a beam *g* mounted on supporting blocks *h*, several rows of aligned expanded metal girders *a* extending in one general direction, and several 85 rows of aligned similar girders *a*⁴ extending in another direction, the girders *a* and *a*⁴ being inclined relatively to each other into a curved structure, and the girders *a* being fixed at their ends to the web portions of the girders *a*⁴, and the girders *a*⁴ being fixed at their ends to the web portions of the girders *a* in the manner described with reference to Figs. 3 and 4.

What I claim is:—

1. A lattice-work structure for use in constructing roofs, walls, and the like, comprising a plurality of rows of aligned metal girders each consisting of a slotted bar stretched in a direction perpendicular to its length to 100 give maximum depth at about the mid portions of the girders, a plurality of rows of similar aligned girders extending in another direction, the girders of all the said rows being disposed with the web portions substantially 105 perpendicular to the lattice-work structure, and the girders of each row being fixed with their ends to about the mid portions of the webs of the girders of the rows extending in the other direction, and means for strengthening the mid portions of the girders.

2. A lattice-work structure for use in con-

structing roofs, walls, and the like, comprising a plurality of rows of aligned expanded metal girders extending in one general direction, a plurality of similar aligned girders extending in another direction, all the said girders being disposed with their web portions substantially perpendicular to the lattice-work structure, strengthening members secured to the web portions of the girders at about the mid portions thereof, and means for securing the ends of the girders of each row to the said strengthening members secured to the web portions of the girders of the rows extending in the other direction.

3. A lattice-work structure for use in constructing roofs, walls, and the like, comprising a plurality of rows of aligned expanded metal girders, a plurality of rows of similar aligned girders extending in another direction, all the said girders being disposed with their web portions substantially perpendicular to the lattice-work structure, and said girders being inclined relatively to each other into a curved structure, and means for strengthening and bracing the said mid portions of the webs of the girders and for securing thereto the adjacent ends of other girders extending in another direction.

4. A lattice-work structure for use in constructing roofs, walls, and the like, comprising a plurality of rows of aligned expanded

metal girders extending in one general direction, a plurality of rows of aligned similar girders extending in another direction, said girders being disposed with their web portions substantially perpendicular to the lattice-work structure and being inclined relatively to each other into a curved structure, strengthening members secured to the web portions of the girders at about the mid portions thereof, and means for securing the ends of each girder to the said strengthening members of girders extending in another direction.

5. A lattice-work structure for use in constructing roofs, walls, and the like, comprising a plurality of rows of aligned expanded metal girders having the same general direction, a plurality of similar rows of aligned expanded metal girders disposed angularly of said first-named rows and in another general direction, the girders of all the rows being disposed with their web portions substantially perpendicular to the lattice-work structure, plates fixed to the mid portions of the web portions of the girders, and angle irons fixed to said plates, the girders of the rows having one general direction being fixed with their ends to the angle irons of the girder of the rows having another general direction.

In testimony whereof I have affixed my signature.

HEINRICH JUCHO.
